1

This invention relates to electron discharge devices and circuits therefor, and particularly to magnetrons employing secondary emissive cold cathodes. The invention is especially applicable to amplifiers for high power use, such as may be employed for induction heating purposes, though not limited thereto.

The present invention contemplates the use of a magnetron employing secondary electron emission from cold cathodes produced by electron bombardment of the cold cathodes under the influence of electromagnetic fields oscillating at a frequency much greater than the input and output frequency.

In order to initiate electron emission, I provide in a magnetron a relatively small emission hot cathode for producing a priming current, and I control this electron priming current by means of a grid, thereby making the priming current almost independent of electron emission from the hot cathode, so long as the emission is equal to or greater than the priming current. This small control emission is made to impinge upon a cold cathode in order to produce secondary electrons. Secondary electrons (under the influence of the magnetic field, a direct current electric field, and very high frequency electromagnetic fields) are made to circulate out from the cold cathode and back to it with increased energy, so as to produce more secondary electrons and this process is repeated until a relatively very large electro emission is made available to supply current to an output anode. During the process of secondary emission multiplication, the electrons (in transit from the cold cathode out and back) are given a component of motion parallel to the axis of the vacuum tube but away from the region of the hot cathode toward the region of the output anode. When this motion in an axial direction is great enough, but not too great, the production of secondary emission can continue only so long as the priming emission from the hot cathode is allowed to fall upon the cold cathode. Thus, the very large emission from the cold cathode may be started and stopped by starting and stopping the very small current from the hot cathode. If the current from the hot cathode is started and stopped at a rate of, let us say, 50,000 current pulses per second, then the amplifier will supply 50,000 cycles per second output power and the output power can be made to be enormously greater than the input control power.

A cold cathode has many practical advantages for the production of secondary emission. By making it the coldest part of the internal surface

2

of the evacuated magnetron tube, it may be kept continuously activated by an alkali metal such as caesium. The caesium in the vacuum tends to migrate continuously to the coldest surface in a vacuum vessel. If the cathode provides the coldest surface, then the caesium will accumulate there and provide a surface of large secondary emission ratio which is continuously healing itself by caesium condensation as the caesium is sputtered off by ion bombardment. In addition, electron bombardment will not be able to remove the caesium due to a rise in temperature and the consequent rapid re-evaporation, if the cathode is adequately cooled as is contemplated in the present invention.

In general the vapor pressure of the activating material in the main body of the tube will be that corresponding to the cathode temperature and the lower the cathode temperature the lower will be the vapor pressure. In practice, the vapor pressure may be kept low enough to make the effects of ionization of vapor upon the tube characteristics quite small.

When using relatively large tubes, I propose to cool the secondary emission cathode by a continuous flow of water, or any other suitable cooling fluid, in a manner which will assure that the secondary emissive cold cathode is the coldest surface in the tube. In small tubes, air cooling properly applied can accomplish a like result. Since a cold cathode is used in the present invention in order to produce the emission which appears as the anode current, I avoid completely the difficult problem of trying to produce large thermionic cathode emission, such as is encountered in conventional amplifier tubes.

The following is a more detailed description of the invention, in conjunction with the drawing whose single figure illustrates in cross-section a magnetron tube constructed in accordance with the principles of the invention, and suitable circuits therefor.

Referring to the drawing, there is shown a magnetron oscillation generator used as an amplifier tube, and having a small hot cathode 1, a control electrode or grid 2, so to speak, surrounding the hot cathode, and spaced therefrom in an axial direction there is provided a non-thermionic or cold cathode 3 suitably coated with secondary emissive material such as caesium. It should be noted that the hot cathode, control electrode and the cold cathode are arranged along the axis of the tube. Surrounding these elements there is provided a multiple cavity anode resonant structure 33 having a plurality of inwardly pro-

jecting target portions. This multiple cavity anode structure may follow the principles described in my United States Patent 2,217,745, granted October 15, 1940. Spaced from and surrounding the cold cathode 3 in axial relation thereto is an anode 4 for collecting the secondary emissive electrons emitted from the cold cathode. The anode structures 33 may constitute the envelope per se and this envelope is suitably sealed by means of glass seals 6. The interior of the envelope is suitably evacuated. A coil 5 surrounds the anode structure for producing a magnetic field which is parallel to the axis of the tube along which lies the hot cathode and the cold cathode, and this field acts transversely of the cathode-to-anode structure path. Obviously a permanent magnet may be used in place of the coil, to produce the magnetic field, as is well known in the magnetron art.

The cold cathode 3 is hollow in its interior and is cooled by means of cooling water supplied to an inlet pipe 7. The outlet pipe is designated 8. The direction of water flow is indicated in the drawing by means of the arrows. Reference is made to my co-pending applications, Serial No. 534,066, filed May 4, 1944, now Patent No. 2,420,744 issued May 20, 1947, and Serial No. 553,138, filed September 8, 1944, now Patent No. 2,448,527, issued September 7, 1948, for descriptions of cathode cooling systems.

The field coil 5 is energized by a source of direct current 9 over leads 10. The variable resistor 11 provides a means for varying the amount of magnetizing current fed to the field coil. The thermionic cathode 1 is heated by means of a source of alternating current power fed to the primary winding of iron core transformer 12. The secondary winding of the transformer 12 is connected via leads 13 to the terminals of the hot cathode 1. The anode 4 is maintained at a relatively high positive potential relative to both the hot cathode 1 and the control electrode 2 by means of a direct current power source 14. It should be noted that the positive terminal of the direct current power source is connected to the output anode 4 through a tuned output circuit 15. The negative terminal of the high voltage power source 14 is connected by means of lead 16 to a tap on a resistor 17; one terminal of which is connected to a tuned input circuit 18 and thence to the control electrode 2 over a lead 19, and the other terminal of which is connected to the hot cathode 1 by means of lead 20 and one of the filament heating leads 13. A suitable source of low direct current potential 21 is connected to these terminals of the resistor 17. It will thus be seen that the control electrode 2 is maintained at a low negative direct current potential relative to the cathode by means of source 21, while the small hot cathode 1 is at a direct current potential which is more positive than the potential of the cold cathode 3. This is because the cold cathode 3 is connected by way of lead 22 to the negative terminal of the high voltage direct current power source 14.

An input source of alternating current power 23 (such as power of low radio frequency) is magnetically coupled to the parallel tuned input circuit 18 which is connected between the control electrode 2 and the hot cathode 1. Element 24 designates a by-pass condenser for energy of the low radio frequency supplied by source 23 and this condenser is connected between one cathode lead 13 and the tuned circuit 18. Element 25 designates another by-pass condenser

which is connected across the high voltage direct current power source 14 for by-passing energy of the operating frequency.

In order to set up a very high frequency electromagnetic field in the multiple cavity resonator anode structure 33, there is provided a source 26 which is coupled via a coaxial transmission line 27 to a coupling loop 28 located in the interior of the anode structure. Source 26 furnishes very high frequency power to the resonator at the resonant frequency of the multiple cavity anode structure. In this manner the system relies upon the energy from source 26 to build up a field in the resonator rather than on any self-oscillating characteristic of the magnetron, although some self-regeneration may take place after emission is built up. In practice, source 26 is of such magnitude as to set up a voltage of several thousand volts between adjacent target portions of the cavity resonator anode structure 33. The frequency of source 26 may be of the order of hundreds or thousands of megacycles and, of course, will be matched by the resonant frequency of the anode structure.

In the operation of the system of the invention, the source 23 of low radio frequency potential serves to control the flow of priming current or initial electrons from the hot cathode 1 without which priming electrons secondary emission multiplication cannot readily take place from the cold caesium coated cathode 3. It will thus be seen that the input radio frequency from source 23 can be used to determine whether or not oscillations take place and, if they do take place, to control the frequency of oscillations. In practice at present, source 23 can have a frequency anywhere in the range of audio or moderate radio frequencies from zero up to about one megacycle. The tuned output circuit 15, on the other hand, can have the same frequency as that of source 23 or a frequency harmonically related to the frequency of source 23.

During the operation of the magnetron system of the invention, the anode 4 (which is concentrically positioned with respect to and envelopes the cold cathode 3) is maintained at an average large positive direct current output potential, and this anode potential varies cyclically at the input and output frequency above and below the direct current potential. The anode potential relative to the cold cathode 3 reaches a relatively low positive value at the time of maximum electron current flow between the anode 4 and the cold cathode 3. Stated otherwise, when the output anode 4 is at a relatively small positive potential (due to the peak instantaneous radio frequency voltage in the tuned output circuit opposing the direct current anode potential), the number of electron multiplications on the cold coated cathode 3 is large, thus resulting in large total emission from the cold cathode and hence large instantaneous output anode-to-cold cathode current. When the anode is at its highest positive potential, due to the instantaneous value of radio frequency voltage aiding the direct current anode potential, electron multiplications on the cold cathode are few or none and the instantaneous output anode-to-cold cathode current is very small. It will thus be seen that the higher the value of instantaneous output anode-to-cold cathode voltage, the lower will be the anode current, and the lower the value of instantaneous output anode-to-cold cathode voltage the higher will be the anode current. This

is the condition for negative resistance oscillations.

At the time when peak anode-to-cold cathode current is desired, the moderate positive potential on the output anode 4 and the instantaneously negative potential of the hot cathode 1 and its control electrode 2 with respect to the cold cathode 3 provides a component of electric field around the cold cathode which causes electrons in transit out from the cathodes through the magnetron anode structure and back to the cold cathode to be subject to an acceleration in an axial direction away from the hot cathode and toward the output anode 4. In a tube suitably designed and operated, this acceleration toward the output anode 4 is an important factor in the amplification process.

When the output anode potential is low, the axial acceleration of the hopping electrons toward the anode will be small. This results in a large number of hops before the effect of a group of electrons originating at the hot cathode reaches the output anode in the form of a large pulse or component of anode current. Because of the large number of hops, secondary emission multiplication of the initial current may be enormous and result in an enormous amount of anode current as compared with the current from the hot cathode.

Depending upon the character of the surface of the cold cathode 3, the caesium coating can provide up to about ten secondary electrons for each impacting electron. Under practical conditions, in the present type of tube I would expect to obtain about $\sqrt{10}$ secondary electrons per primary electron, or ten to one for each two electron hops. The multiplication of the initial current can, accordingly, be approximately expressed by the relation:

$$\frac{I_a}{I_i} = (10)^{h/2}$$

where I_a is the anode electron current, I_i is the initial priming current, and h is the number of successive electron hops between the hot cathode and the output anode.

Let it be assumed that I_a is 100 amperes, and I_i is 0.0001 ampere (0.1 milliampere), then $I_a/I_i = (10)^6$ and $h=12$ hops. Thus, in practice, there may be ten or more electron hops from the hot cathode to the output anode.

I prefer that, at moments of minimum instantaneous output anode-to-cold cathode potential, the number of electron hops be considerably greater than the minimum number required so that the anode current will be space charge limited rather than emission limited. This makes it possible to obtain a high power conversion efficiency without instability or critical adjustments.

It may be noted that once the priming current has caused the building up of a space charge limited secondary emission current, the priming current may be expected to lose control of the anode current. Therefore, if the anode potential were maintained continuously at a rather low value, turning on the priming current may start the anode current but turning off the priming current will not stop the anode current again. This is analogous to the trigger action of Thyratron and Ignitron type gas discharge tubes, and tubes of the present invention may be used as a substitute for Thyratron and Ignitrons.

However, when the potential on anode 4 is oscillatory due to the reaction of the tuned out-

put circuit 15, the anode potential will not remain low but will oscillate upward again from the minimum value. As it does, it automatically reduces the number of hops from one end to the other of cold cathode and reduces the production of secondary emission to a low value, or interrupts it altogether if the priming current has, in the meantime, been cut off by the input control. Thus the controlled priming current from hot cathode 1 can initiate the anode current at the proper point of the cycle but interruption of the anode current takes place due to the rise in anode potential.

If the priming current is made to be small enough, and the maximum secondary emission current multiplication great enough, it is possible to leave the priming current on continuously, in which case the tube and circuit will be able to oscillate at any frequency, over a broad band, to which the output circuit 15 is tuned. This may be a desirable condition of operation in industrial applications where frequency stability may be less important than flexibility and automatic adjustment of the oscillator to changing load conditions.

It is to be noted that, in practice, some conditions at the cold cathode might result in production of an effect which consists of a persistence of some emission after impacting electrons have been stopped. This phenomenon could result in the cold cathode supplying its own priming current in a manner to cause loss of control by means of the input power. This would not be objectionable in industrial applications but might be very objectionable in some forms of communications.

It is also probable that the initial priming current source can be omitted entirely in tubes for industrial application and reliance had upon cosmic rays, photo-emission, cold emission accompanying evaporation and condensation, or other causes to provide all the priming current needed to start the emission. In this connection, it may be noted that a single electron leaving the cold cathode at a proper time is all that is needed to initiate growth of emission up to space charge limiting, brought about by the very high frequency electric fields in the device.

It is of some interest to note that the cathode power (electron bombardment power) required to produce emission from the cold cathode is automatically applied and cut off (as the multiplication occurs or ceases) as needed, so that the average power required to produce emission may be much less than would be required to produce the same peak emission in a system employing merely a hot cathode, where the emission must be produced or made available continuously rather than in pulses as needed.

A factor to be considered in connection with the application of very high frequency power to the anode structure is that the length of transmission line 27 and loop 28 coupling source 26 to the anode structure 33 should be short and of such a length that, as the secondary emission from the cold cathode waxes and wanes, the resulting change in load impedance and tuning of the anode structure will automatically vary the load resistance presented to the source of very high frequency power in a direction tending to hold more or less constant amplitude electric fields. This is accomplished by making the coupling line with its coupling loops effectively an integral number of half waves long and adjusting the relative frequency of the source 26 and

the resonant frequency of the anode structure in such a way as to provide a maximum loading of the source 26 when space charge due to secondary emission from the cold cathode is present and a minimum loading when it is not. That is, the effective loading should appear at source 26 as though the length of the line 27 between source 26 and cavity resonator 33 is zero.

If the design of the system is such that self-oscillation occurs at the frequency of source 26 after the circuit has been started to operate, then it may be advantageous to change the adjustment of the transmission line 27 from the values specified above. In such a case the coupling and tuning of the line may better be adjusted for a maximum of power transfer when there is no space charge built up.

Only experience with particular tubes and circuit assemblies can provide a reliable guide to the best combinations and adjustments for use in each case.

In order to start the magnetron of the invention operating, it may be advisable to first apply a low anode direct current potential and to raise this potential until oscillations begin, then to continue raising the anode potential up to the normal operating value.

What is claimed is:

1. An electron discharge device comprising a thermionic cathode, a control electrode in the path of the electrons emitted by said thermionic cathode, a secondary emissive cold cathode spaced from said thermionic cathode and having an effective electron emission surface appreciably greater than the electron emission surface of said thermionic cathode, a resonant structure surrounding said cathodes, means coupled to said resonant structure for setting up a very high frequency electromagnetic field in said resonant structure, an output anode adjacent said cold cathode for collecting electrons emanating from said cold cathode, means coupled between said control electrode and thermionic cathode for supplying alternating current energy thereto, and an output tuned circuit coupled to said output anode.

2. An electron discharge device comprising a thermionic cathode, a control electrode in the path of the electrons emitted by said thermionic cathode, a secondary emissive cold cathode spaced from said thermionic cathode and having an effective electron emission surface appreciably greater than the electron emission surface of said thermionic cathode, a cavity resonator surrounding said cathodes, a source of high frequency power coupled to said cavity resonator for setting up a high frequency field therein, an output anode adjacent said cold cathode for collecting electrons emanating from said cold cathode, a source of alternating current energy coupled between said control electrode and thermionic cathode, a parallel tuned output circuit coupled to said output anode, and means for supplying said output anode with a relatively high direct current positive voltage relative to said thermionic cathode and control electrode.

3. An electron discharge device comprising a thermionic cathode, a control electrode in the path of the electrons emitted by said thermionic cathode, a secondary emissive cold cathode spaced from said thermionic cathode and having an effective electron emission surface appreciably greater than the electron emission surface of said thermionic cathode, a multiple cavity resonant structure surrounding said cathodes, a source of high frequency power coupled to said cavity res-

onant structure for setting up therein a high frequency field, an output anode adjacent said cold cathode for collecting electrons emanating from said cold cathode, a source of alternating current energy coupled between said control electrode and thermionic cathode, a parallel tuned output circuit tuned to the frequency of said source of alternating current or a frequency harmonically related thereto coupled to said output anode, and means for supplying said output anode with a direct current potential which is highly positive relative to said thermionic cathode, control electrode and cold cathode.

4. An electron discharge device comprising a thermionic cathode, a control electrode in the path of the electrons emitted by said thermionic cathode, a secondary emissive cold cathode spaced from said thermionic cathode and having an effective electron emission surface appreciably greater than the electron emission surface of said thermionic cathode, a resonant structure surrounding said cathodes, a source of high frequency power having a frequency the same as the resonant frequency of said resonant structure coupled to said resonant structure for setting up an electromagnetic field in said resonant structure, an output anode adjacent said cold cathode for collecting electrons emanating from said cold cathode, a source of alternating current energy coupled between said control electrode and thermionic cathode, and an output tuned circuit coupled to said output anode.

5. A magnetron electron discharge device comprising a controllable source of priming electrons, a cold cathode spaced from said source and adapted to be bombarded by the electrons from said source of priming electrons, said cold cathode being coated with secondary emissive material, means for cooling said cold cathode, a cavity resonant structure surrounding said source of priming electrons and said cold cathode, a source of relatively high frequency power of a frequency the same as the resonant frequency of said cavity structure coupled to said structure, an output anode adjacent to said cold cathode for collecting the secondary electrons emitted by said cold cathode, a source of power of relatively low radio frequency coupled to said controllable source of priming electrons, and an output tuned circuit coupled to said output anode, said output tuned circuit being resonant to a frequency $n f$, where n is an integer and f is the frequency of the said source of low radio frequency power.

6. An electron discharge device comprising a thermionic cathode, a control electrode in the path of the electrons emitted by said thermionic cathode, a secondary emissive cold cathode spaced from said thermionic cathode and having an effective electron emission surface appreciably greater than the electron emission surface of said thermionic cathode, a resonant structure surrounding said cathodes, means for producing a magnetic field acting transversely to the path between said cold cathode and the surrounding surface of said resonant structure, an output anode adjacent said cold cathode for collecting electrons emanating from said cold cathode, means for setting up an electromagnetic field in said resonant structure, a source of alternating current coupled between said control electrode and thermionic cathode, an output tuned circuit coupled to said output anode, and means in series with said output tuned circuit for supplying said output anode with a direct current polarizing potential which is highly positive relative to said

thermionic cathode, control electrode and cold cathode.

7. A magnetron amplifier comprising an envelope in the form of a cavity resonant structure, a thermionic cathode and a spaced tubular secondary emissive cold cathode both arranged along the axis of said envelope, a control electrode for controlling the flow of electrons from said thermionic cathode, means for supplying a magnetic field acting parallel to said axis, an output anode adjacent to said cold cathode, a source of high frequency power coupled to said cavity resonant structure for setting up therein a high frequency field, means for supplying said output anode with a direct current potential which is positive relative to said cathodes and said control electrode, a source of alternating current coupled between said thermionic cathode and said cold cathode, an output tuned circuit coupled to said output anode.

8. A magnetron tube and circuit therefor comprising a relatively small thermionic cathode, an elongated secondary emissive cold cathode spaced from said thermionic cathode, both said cathodes being arranged along the axis of said tube, a control electrode for controlling the electron emission from said thermionic cathode, a tubular output anode in coaxial relation to and enveloping a portion of said cold cathode which is furthest removed from said thermionic cathode, a resonant structure surrounding said cathodes and said output anode, means for setting up an electromagnetic field within said resonant structure, a source of alternating current coupled between said thermionic cathode and said control electrode, a tuned output circuit coupled to said output anode, and means for supplying said output anode in series with said tuned circuit with a direct current potential which is positive relative to said cathodes and said control electrode.

9. A magnetron tube and circuit therefore, comprising a relatively small thermionic cathode, an elongated secondary emissive cold cathode spaced from said thermionic cathode, both said cathodes being arranged along the axis of said tube, a control electrode for controlling the electron emission from said thermionic cathode, a tubular output anode in coaxial relation to and enveloping a portion of said cold cathode which is furthest removed from said thermionic cathode, a multiple cavity resonant structure having a plurality of inwardly projecting electron target portions surrounding said cathodes and said output anode, means for producing a magnetic field acting transversely to the path between the axis of said tube and said resonant structure, a source of high frequency energy coupled to said resonant structure in the interior of one of the cavities thereof for setting up an electromagnetic field at the frequency of said resonant structure, a source of alternating current coupled between said thermionic cathode and said control electrode, a tuned output circuit coupled to said output anode, and means for supplying said output anode in series with tuned circuit with a direct current potential which is positive relative to said cathodes and said control electrode.

10. A system in accordance with claim 8, characterized in this that said source of high frequency energy is coupled to said resonant structure by means of a line and coupling probe whose overall electrical length is substantially an integral number of half waves long at the frequency of said source.

11. The method of operating a magnetron hav-

ing a thermionic cathode and an elongated cold secondary emissive cathode, which comprises initiating a flow of electrons from said thermionic cathode, applying to said magnetron a high radio frequency electric field, a unidirectional electric field and a magnetic field acting parallel to said elongated cold cathode, periodically interrupting the flow of electrons from said thermionic cathode, collecting secondary electrons from said cold cathode, resonating said collected electrons at a frequency related to the rate of interruption of the electrons from said thermionic cathode, and cyclically varying said unidirectional electric field at said resonating frequency.

12. A negative resistance oscillator comprising a vacuum tube having a non-thermionic secondary emissive cathode, an anode surrounding an extended portion of said cathode, a resonant structure surrounding said cathode and anode, means for setting up a high frequency electromagnetic field in said resonant structure, and a tuned circuit coupled to said anode, a source of potential coupled to said anode through said tuned circuit for supplying thereto a potential which is positive relative to said cathode, and circuit components for causing secondary emission from said cathode to be large when the anode to cathode potential is small and secondary emission to be small or zero when the anode to cathode potential is high.

13. A device for multiplying secondary electron emission by multiple electron closed impacts upon a cold cathode, in response to very high frequency electromagnetic fields, said device having a non-thermionic secondary emissive cathode, an anode surrounding an extended portion of said cathode, and a tuned circuit coupled to said anode, a source of potential coupled to said anode through said tuned circuit for supplying thereto a potential which is positive relative to said cathode, and circuit components including a resonant structure surrounding said anode and cathode for causing the multiplication from said cathode to be large when the anode-to-cathode potential is low but small or zero when the anode-to-cathode potential is large.

14. A magnetron comprising an evacuated enclosing housing having an anode therein, said anode providing a cathode cavity longitudinally central thereof, a cathode coaxial of and within said cavity and emission from which is substantially secondary electrons only, and means at one end of said cathode for conducting a cooling medium both to and from said cathode.

15. A magnetron comprising an evacuated enclosing housing having an anode therein, said anode providing a cathode cavity longitudinally central thereof, a main cathode coaxial of and within said cavity and emission from which is substantially secondary electrons only, means at one end of said cathode for conducting a cooling medium both to and from said cathode, and an auxiliary cathode at the opposite end of said main cathode from said means.

16. A magnetron comprising an evacuated tube having an anode, said anode providing a cathode cavity longitudinally central thereof, a cathode coaxial of and within said cavity and emission from which is substantially secondary electrons only, and means at one portion of said cathode for conducting a cooling medium both to and from said cathode.

17. A magnetron comprising a metallic anode resonator providing a cavity longitudinally central thereof, a main cathode coaxial of and with-

11

in said cavity and coated with secondary emissive material, an auxiliary cathode adjacent said main cathode for supplying a primary electron current for the main cathode, and means at one end of the said main cathode for conducting a 5 cooling medium to and from said main cathode.
